UNITED STATES PATENT OFFICE.

HERRIOTT S. WARNOCK, OF CHICAGO, ILLINOIS, ASSIGNOR TO THE PRINTING MACHINERY COMPANY, OF CINCINNATI, OHIO, A CORPORATION OF OHIO.

CLAMPING DEVICE.

Application filed June 7, 1924. Serial No. 718,462.

To all whom it may concern:

Be it known that I, HERRIOTT S. WARNOCK, a citizen of the United States, residing at Chicago, in the county of Cook and State 5 of Illinois, have invented new and useful Improvements in Clamping Devices, of which the following is a specification.

This invention relates broadly to clamping devices and more particularly to an improved clamp specially adapted for employment as a printing appliance for supporting and retaining printing plates, forms and the like in position on a printing press platen, roll or the like.

15 While my invention is illustrated and described as employed for retaining a printing plate, it will be understood that this invention may be advantageously employed elsewhere and therefore finds a wide field of 20 utility for other purposes.

In the printing of special work it is customary to employ either a bed plate having perforations, and to which bed plate a printing plate such as an electrotype is secured 25 by the provision of retaining devices which seat in the perforations at convenient points and clampingly engage the printing plates. Heretofore, the devices known to me have 30 for the most part been complicated, difficult to insert and clamp into position, and expensive to manufacture.

I have made improvements in the devices thus employed, for instance, that disclosed 35 and claimed in my Patent #1,418,112, and the present invention is a still further improvement, and has for its principal objects and advantages the provision of an improved clamping device characterized by the embodiment therein of improved supporting 40 means; the provision of an improved clamping device including supporting means for the clamp characterized by the absence of moving parts; the provision of an improved means for frictionally supporting a clamp; 45 the provision of an improved clamp including improved means for fixedly supporting and retaining the clamp in a recess; the provision of an improved device of the character referred to which is characterized by simplicity, compactness and increased utility, due 50 to the absence of numerous moving parts; and the provision of a device of the character described, which, when employed for retaining printing plates by insertion in 55 openings in a bed plate, automatically en-

gages with the bed plate and thus simplifies the attachment and mounting of the clamp in position.

The foregoing and such objects and advantages as may appear or be pointed out 60 hereinafter are attained by the structure illustrated in the accompanying drawing; in which:

Figure 1 is a plan elevational view of a printing bed plate and printing plate illustrating an application of this invention; 65

Figure 2 is an enlarged fragmentary elevational plan view;

Figures 3 and 4 are vertical sectional views taken on the lines 3-3 and 4-4, respectively, of Figure 1, looking in the direction indicated by the arrows; 70

Figure 5 is a view similar to Figure 3 illustrating the manner of introducing the device in use; and 75

Figure 6 is a perspective view of a part of the invention.

Referring more particularly to the drawing, and first to Figure 1, I have illustrated a bed plate 5, which, of course, may 80 take a cylindrical or curved shape where employed on a printing press roll.

The bed plate 5 is provided with a plurality of round openings 6 which serve as sockets for the reception of one or more of the clamping devices of this invention generally designated 7, in Figure 1, for clampingly retaining the electrotype or other printing plate 8 in proper position. The openings 6 are annularly enlarged at their inner or bottom edges, as at 9-9 to afford shoulders 10-10 for a purpose which will presently appear. It will also appear that, where convenient, the annular shoulders 10 may be omitted. 95

The clamping or holding device of this invention generally includes a substantially U-shaped frame F for engagement in one of the openings in the bed plate, and a clamp-jaw C variably mounted in said frame. 100

Referring now in detail to Figures 2 to 6, the frame F includes a base portion 11, and integral substantially parallel spaced side walls 12-12, said walls being substantially normal to the base portion 11. 105

As will best be observed from an inspection of any of Figures 3, 4, or 5, both of the walls 12 have their outer side edges 13-14 relatively converging toward the base 11, so that the frame is thereby given a gen- 110

erally tapered configuration as viewed in, say, Figures 3 and 5. The width of the walls 12 at their outer ends is such that the outer longitudinal corners 15-15 will, near the outer corners 15^a, contact with the wall of the openings 6 when the device is inserted, as indicated at 16-16, Figs. 2 and 3. This contact is quite snug as will later appear more particularly. The edges 14 are substantially perpendicular to the base 11, the edge 13 being inclined.

10 The base 11 is extended to form a locking member or lug 17, which is of a length and curvature which permits insertion of the device freely into the opening 6 to a predetermined point, the curved edge 17^a of the lug 17 being at such a distance from the inner opposite corners 18 of the walls and base as to just permit insertion of the device 20 vice canted as shown in Figure 5.

The side walls 12 of the frame F are provided with aligned openings 19-19, and a transverse pin 20 is secured fixedly in said openings. Beyond the openings there are 25 provided guiding slots 21-21 in the walls 12, said slots being complementary to each other and angularly disposed relative the edges 13 and 14 of the walls 12, and extending from points adjacent to the edges 13 30 and 14 inwardly toward the inclined edge of said walls.

The clamping device is in its entirety contained within the frame F, with the exception of the jaw C hereinbefore referred to, 35 and this clamping mechanism includes a yoke 22 having a pair of ears, only one, 23, of which appears, (see Figure 4) said ears being journaled upon the pin 20 and lying against the inner faces of the walls 12. 40 The yoke is thus angularly displaceable about the pin 20. As will be observed from an inspection of Figure 4, the jaw C is integrally formed upon the outer end of the yoke 22.

45 Journaled upon the pin 20 between the ears 23, there is the eye member 24, which latter is provided with a radial extension 25 having a bearing socket 26.

The actuating member comprises a 50 threaded shank 27, having a reduced axial portion 28 which revolvably seats in the socket 26, the outer end of the shank having a cylindrical portion 29 which revolvably seats in the bearing socket 30 formed beneath the jaw, and said socket having a reduced bore 31. The cylindrical portion 29 is provided with a polygonal recess 32 and a tool for rotating the shank 27 may be inserted through the bore 31 into recess 32.

60 The tool thus engaging the shank is advantageous in that it simplifies the construction and manufacture and facilitates engagement of the tool with the clamp actuating device.

65 A cross head 33 is in threaded engage-

ment with the shank 27, said cross-head having trunnions 34 complementary to and receivable in the guide slots 21, so that when the shank 27 is rotated the cross head is reciprocated and thereby displaces the trunnions 34 in the slots 21 and this motion is imparted to the yoke and jaw to angularly displace same about the transverse pin 20 as an axis.

70 The jaw C is undercut as at 35 to form a beveled portion which engages with a complementary surface 36 on the edges of the printing plate 8 or other object to be held, said jaw C being relatively wide as shown in Figure 2 so as to afford a wide area of contact with the plate or other object.

75 When the device 7 is inserted into the opening 6 it is first placed as shown in Figure 5. Pressure applied to the outer end of the device forces it downwardly into the opening and when the lug 17 reaches the shoulder 10, said lug snaps under said shoulder and retains the device in the position shown in Figures 2, 3 and 4.

80 The dimensions of the frame F, lug 17, and the openings 6 are such that simultaneously with the engagement of the lug 17, with the shoulder 10, the corners 15-15 of the edges 13 and 14 of the walls 12 abut the wall of the opening 6 as seen best in Figures 2 and 3; and the upper corners 15^a 85 similarly abut the wall of the opening 6, so that the device is snugly and firmly suspended in the opening. The lug 17 prevents displacement in one direction, and the snug engagement of the walls 12 with the opening 6 and the engagement of the jaw C with the work prevents the device from passing entirely through the opening 6.

90 It will be obvious that where projection of the lug 17 beyond the inner face of the plate 8 is not objectionable, the shoulder 10 may be omitted.

95 The base 11 may be provided with an opening 11^a which facilitates assembly of the parts and permits free swinging of the eye 24 and associated parts during adjustment.

100 From the foregoing it will be observed that in the device of the present invention the only moving parts are those of the clamp and actuating mechanism and that no moving parts actuated by either the clamp or otherwise are required for supporting or retaining the device in operative position, the supporting and retention of the device being accomplished solely by relatively fixed members, thus producing a wedge like or frictional engagement of the device with the opening.

105 This mounting of the device has the added advantage of permitting mounting of the device with its jaw presented in any desired direction, and eliminates notches, grooves or other keyways in the opening 6 for holding

purposes, thus simplifying the construction of the bed plate.

To remove the device a wedge or other suitable tool is inserted between the edge 13 of one of the walls 12 and the wall of the opening 6 and by applying pressure the device may be sprung out of its seating position and then readily removed. Removal may also be effected by insertion of a bar 10 between the yoke 22 and the wall of the opening 6, and applying pressure to cause the lug 17 to disengage from the shoulder 10.

I claim:

1. The combination with a supporting member having a recess or opening therein, of a frame, a clamp on said frame, and means on said frame for frictionally engaging the wall of said opening.

2. The combination with a printing foundation having a recess, of a clamp for retaining printing forms on said foundation receivable into said recess and adapted to be frictionally engaged with the wall of said recess.

3. The combination with a printing foundation having a recess, of a clamp for retaining printing forms on said foundation receivable into said recess and provided with integral means for frictionally engaging the wall of said recess.

4. The combination with a supporting member provided with a recess having an offset shoulder, of a clamp including supporting frame having frictional engagement 35 with the wall of the recess and fixed means positively engaging said shoulder.

5. The combination with a printing foundation having a recess, of a clamp for retaining printing forms on said foundation receivable into said recess and having a wedge like engagement with a part of the recess and positive engagement with another part of the recess.

6. In a device of the character described, 45 in combination, a clamp, a supporting frame therefor including parallel spaced walls and an end wall having an extending lug, and the longitudinal edges of said parallel walls converging toward said end wall.

50 7. In a device of the character described, the combination with a bed plate having a recess therein, and a shoulder of a clamping member including a frame adapted to be inserted into said recess and to engage with the recess at a plurality of points, and a relatively fixed locking member on said frame adapted to engage said shoulder.

8. In a device of the character described, 60 in combination, a supporting frame substantially rectangular and provided with a fixed locking member, said frame being adapted, when inserted in an opening, to abut against the wall of the opening and said locking member engaging an edge of the opening.

65 9. In a device of the character described,

in combination, a supporting frame substantially rectangular and provided with a fixed locking member, said frame being adapted, when inserted in an opening, to wedge against the wall of said opening and to 70 fixedly engage with one edge of the opening.

10. The combination with a base plate provided with an opening, of a supporting frame for a clamp or the like, of dimensions permitting said frame to be freely inserted 75 into said opening to a predetermined point and then adapted to wedge in said opening and simultaneously engage positively with a part of the wall of said opening.

11. The combination with a base plate 80 provided with an opening, of a supporting frame for a clamp or the like of dimensions permitting said frame to be freely inserted into said opening to a predetermined point and then adapted to wedge in said opening 85 and means on said frame for fixed positive engagement with the wall of said opening.

12. The combination with a base plate provided with an opening, of a supporting frame for a clamp or the like of dimensions 90 permitting said frame to be freely inserted into said opening to a predetermined point and then adapted to wedge in said opening 95 and means fixedly mounted on said frame and adapted to positively engage a part of the wall of said opening.

13. The combination with a base plate provided with an opening, of a supporting frame for a clamp or the like of dimensions 100 permitting said frame to be freely inserted into said opening to a predetermined point and then adapted to wedge in said opening, and means integral with said frame and adapted to positively engage a part of the wall of said opening.

105 14. The combination with a base plate provided with an opening, of a supporting frame, of dimensions permitting same to be freely inserted into said opening to a predetermined point whereupon the frame 110 wedges into the opening, and a fixed extension on said frame for positive engagement with said base plate.

15. In a device of the character described, in combination, a supporting frame including a base and parallel side walls substantially normal to said base, said side walls having their longitudinal edges converging toward said base, and a clamp mounted between said side walls.

120 16. In a device of the character described, in combination, a supporting frame including a base and parallel side walls substantially normal to said base, said frame being of substantially tapering form, and a clamp 125 adjustably mounted upon said frame.

17. In a device of the character described, in combination, a substantially U-shaped frame, and a clamping member supported by said frame on the side walls thereof.

18. In a device of the character described, in combination, a substantially U-shaped tapering frame, and a clamping member supported by said frame on the side walls thereof.
19. In combination, a bed plate having an opening therein, a frame of substantially tapering configuration adapted to wedge into said opening, and a clamping device carried by said frame.
20. In combination, a bed plate having an opening therein, a frame of substantially tapering U-shaped configuration adapted to wedge into said opening, and a clamping device carried by said frame.
21. In combination, a bed plate having an opening therein, a frame of substantially tapering configuration adapted to wedge into said opening, means on said frame for positive engagement with said bed plate and a clamping device carried by said frame.
22. In a device of the character described, in combination, a supporting frame including a base and parallel side walls substantially normal to said base, and a clamping device mounted pivotally between said walls and provided with means for engagement with the wall for angularly displacing said clamp.
23. In a device of the character described, in combination, a supporting frame including a base and parallel side walls substantially normal to said base, and a clamping device mounted pivotally between said walls and provided with means for engagement with the wall for angularly and longitudinally displacing said clamp.
24. In combination, a bed plate having a substantially cylindrical opening therein, a polygonal supporting frame adapted for insertion into said opening and for wedging engagement with the wall there, and a clamp carried by said frame.
25. In combination, a bed plate having a substantially cylindrical opening therein, a polygonal supporting frame adapted for insertion into said opening and for wedging engagement with the wall thereof, means on said frame for positive engagement with the bed plate and a clamp carried by said frame.

In testimony whereof I affix my signature in the presence of two witnesses at 10 South La Salle Street, Chicago, Illinois.
